UNITED STATES PATENT OFFICE

JOHN C. HAGGART, JR., OF ALMA, MICHIGAN, ASSIGNOR TO DETROIT PATENTS HOLDING COMPANY, OF DETROIT, MICHIGAN, A CORPORATION OF MICHIGAN

RADIATOR

Application filed June 30, 1924. Serial No. 723,262.

This invention relates to means for prolonging the life of a radiator by reducing the strains and vibrations to which the more or less delicate core thereof is subjected when in use.

It is well known in the art to which this invention appertains that considerable difficulty has been experienced in the past in safe-guarding the core of a radiator from vibration and road shocks, and preventing the springing of leaks and general break down of the fabricated material composing such cores. This is experienced to a marked extent in motor vehicles of heavy types, such as trucks, particularly where it is not feasible to provide highly efficient shock absorbing means in the vehicle itself; and even where such means are provided the strains set up in the radiator by the motions of the vehicle have still to be contended with.

In order to overcome these disadvantages it has been hitherto proposed to provide in various ways for the stiffening of the radiator with a view to preventing the bending and warping of the shell so that destructive strains between the shell and the core will not be set up, but it will be obvious that such methods will only be effective to the extent of their efficiency in that regard and would still render the core of the radiator liable to the destructive effects of road shocks and vibrations. It is, therefore, the purpose of this invention to effect the isolation of the core from the shell to a great extent, whereby it may be capable of movement with respect thereto and whereby, as a consequence, the said shell may be movable by road shocks and vibrations with respect to the core without transmitting such shocks and vibrations thereto to any such degree as has been the case with devices of the type heretofore referred to.

A still further object is to effect the rigid supporting of the shell of the radiator from the frame or body of the vehicle without affecting such rigid support of the core. And a still further object is to effect the resilient suspension of the core within the shell and in spaced relation to the sides thereof.

Still further objects subsidiary to or re-

sulting from the aforesaid objects or from the construction or operation of the invention as it may be carried into effect, will become apparent as the said invention is hereinafter further disclosed.

In carrying the said invention into effect I may provide a radiator core and a shell of substantially greater width than said core, with a U-shaped saddle secured within said shell the upwardly extending arms of which saddle are spaced wider than the breadth of said core and preferably engaged directly with the inner faces of the sides of said shell, said saddle being adapted to be secured to the frame or body of a vehicle to provide for the rigid supporting thereof on the said shell, and resilient suspension means, such as plate springs adapted to vertical and lateral yielding movement, extending between the arms of said saddle and the edges of said core and supporting said core from said shell. All of which is more particularly described and ascertained hereinafter, by way of example, having reference to the accompanying drawings, wherein

Figure 1 is a front elevation of a radiator embodying the said invention mounted upon the frame of a vehicle, the frame being indicated in section;

Figure 2 is a plan of the same;

Figure 3 is a rear elevation of the said radiator;

Figure 4 is a transverse section of the same, taken on the line 4^x—4^x of Figure 1;

Figure 5 is a side elevation of the said radiator, and

Figure 6 is a vertical section of the same taken on the line 6^x—6^x of Figure 1.

In a preferred form of my device I show the radiator as being mounted as a whole upon the frame 1 of a vehicle by means of a yoke 2 having end members 3 entering the channels of the said frame, this yoke being provided with forwardly extending lugs 4.

The said radiator includes in its construction a shell 5 which may be of any convenient shape rearwardly projecting sides 6 and within this shell is a saddle comprising a base 7, which may have a central depressed part 8 to give crank clearance when necessary, and up-

wardly extending arms 9, the said saddle being in general of a **U** shaped configuration and substantially constructed of a flat metal strip bent or forged to shape and secured to the sides of the said shell by bolts or rivets 10 and 11. These latter bolts are shown as also effecting the attachment of lamp brackets 12 to the said shell. In the application of the saddle to the yoke 2 the base of the saddle 10 rests on the lugs 4 and is secured thereto by means of bolts 12^a so that the shell is thereby rendered for all practical purposes a rigid part of the machine, although it will be obviously from the description hereinafter of the core mounting that where a less rigid mounting of the core may be adopted this would not be detrimental to the core in the same manner as in the construction having fixed cores.

20 The core 13 which will be seen as being of decidedly smaller dimension than the shell and its supporting saddle so that its sides 14 are spaced from the arms 9 of the saddle, and the said core is of such height that it may 25 clear the top of the shell and the base of the saddle when located within the said shell. Thus, when in position, the said core is bounded on the sides by spaces 15 and on the top and bottom by spaces 16 and 17 respectively.

It is required that the said core shall be laterally movable within the arms of the saddle and that such movement shall be damped to prevent it taking place to an undue extent which would minimize the advantages gained by such lateral movement, this damping being effected by inserting in the space between the sides of the core and the arms of the saddle yielding or resilient members which tend to retain the said core centrally disposed with respect to the said arms and the sides of the shell, these means being indicated as in the form of a spring suspension within the shell whereby a virtually floating core is secured.

The suspension members are indicated as being spring plates having marginal ear pieces 18 secured to the side walls of the shell by bolts 19 and provided with forwardly 50 and somewhat inwardly inclined webs 20 which extend into the spaces between the arms 9 of the saddle and the sides 14 of the core and are spaced from the said arms and core to permit lateral flexing of the said web 55 which is bent inwardly to the said core at its lower end 21 and also beneath the said core 22 to provide a support therefor. The upper end of the said web is also bent inwardly at 23 to the core and over the core at 24 to 60 form positioning means therefor, the form of core suspension thus provided effectually centering the core within the shell and at the same time permitting lateral and vertical movement thereof with respect to the shell 65 within desired limits, and in order to relieve

the said suspension means from the total weight of the core and to still further limit its vertical movement I provide shock absorbers in the form of shims 25 of leather or similar material between the base of the core and the base of the saddle and members 26 on the top of the core supporting similar shims 27 between their upper surfaces and the top of the said shell. These means 25 and 27 are also provided for the elimination of friction between the core and the base of the saddle or the top of the shell when the core is moved laterally.

The arrangement described and illustrated ensures the desired minimizing of the transferring of shock to the core from the shell or from the shell mounting which is in this case the saddle, without permitting any excessive or detrimental independent motion of the said core, and also by reason of this feature admits of the radiator shell being either rigidly secured to the frame of the vehicle or otherwise as may be thought necessary or desirable according to the type of vehicle with which it is used or the conditions to be contended with.

This invention may be developed within the scope of the appended claims without departing from the essential features of the said invention and it is desired that the specification and drawings be read as being merely illustrative and not in a limiting sense, except as necessitated by the prior art.

What I claim is:—

1. In a radiator, a shell, a core within said shell, and a rigid core suspension member extending from the shell and supporting the core, flexible members extending from said shell to the core and maintaining said core centrally in said shell, each of said members having an oblique portion at both ends in proximity to the corners of the core, whereby to permit vertical and lateral resiliency.

2. In a radiator, a shell, a core within said shell, and a rigid core suspension member extending transversely in the shell and supporting the core, flexible members extending from the shell to the core and maintaining said core centrally in said shell, each of said members having an angular portion of 45° at both ends in proximity to the corners of the core, whereby to permit vertical and lateral resiliency.

In testimony whereof I affix my signature.

JOHN C. HAGGART, JR.
